UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP HAVING AS TRUSTEES F. B. TOWNE, E. S. TOWNE, J. M. TOWNE, AND F. W. WILSON.

BOOK BACK FOR LOOSE-LEAF BOOKS.

Application filed March 21, 1928. Serial No. 263,273.

This invention relates to the making of backs for loose leaf books, and has for its object to provide a back which will be exceedingly tough, and can be made in any suitable color and external pattern.

This back is preferably made from what is known as "vulcanized fiber" but can be made from any suitable fibrous material.

A detail description of the invention follows which is to be read in connection with the drawings herewith furnished, and in which

Figure 1 is a plan view illustrating one form of the completed invention—

Figure 2 is a plan view illustrating another form of said invention—

Figure 3 is a section at the line 3—3 of Figure 1—

Figure 4 is a section at the line 4—4 of Figure 2—

Figure 5 is a detail elevation of the loose leaf structure fastening means employed in the construction shown at Figure 1—

Figure 6 is an elevation of the loose leaf fastening structure employed in the construction shown at Figure 2—

Figure 7 is an end elevation of the structure shown at Figure 5 and the fiber back assembled in proper relation preparatory to the application of heat and pressure that unites these parts, and

Figure 8 is a side elevation illustrating the arrangement of parts shown at Figure 7.

Similar numerals of reference denote like parts in the several figures of the drawing.

1 is a strip of fibrous material, preferably vulcanized fiber, which, prior to any operations thereon, is flat and of the desired width and length, as shown at Figures 7 and 8.

In making a book back to be used in connection with loose leaf books, the back must be provided with means whereby a loose leaf structure may be secured thereto, and the usual means employed in this connection is an elongated eyelet or rivet. In the present invention an elongated eyelet 2 is used, which at its lower end is headed to a base the latter having downwardly projecting prongs or similar members which are driven into the fiber by the application of heat and great pressure.

The drawings illustrate two simple exem-

plifications of means for securing the eyelets to the fibrous material but the invention is by no means limited to the employment of these particular means, since the eyelets, instead of being headed to a separate means that has depending projections or analogous devices, may be formed integral with such means and it is merely necessary in this connection that the eyelets or rivets and the fastening means be a quasi integral structure.

One form of the invention, so far as the securing means is concerned, is shown at Figures 1, 3, 5, 7, and 8, and in the construction shown in these figures the eyelet 2 is headed to a circular disk 3 that has depending from its periphery prongs 4, and when the strip of fiber with these disks assembled thereon in proper position, as shown at Figures 7 and 8, is placed within the mold and heat and great pressure applied, these prongs will be driven within the fiber, and as the fiber adapts itself to the mold under this heat and great pressure, it will become concavo-convex in cross section, and since the fiber is exceedingly tough the prongs will be firmly grasped therein and will be bent out laterally during this concavo-convex formation, as shown at Figure 3, thus securely anchoring the eyelets within the fiber.

Referring to the construction shown at Figures 2, 4, and 6, the eyelets are headed to a rectangular plate 5, and two opposite edges of the latter are turned downwardly as shown at 6, and when heat and great pressure are applied, these parts 6 will be forced into the fiber, and as the latter is rendered concavo-convex in cross section by the continued application of the heat and pressure, these parts 6 will be distended as shown at Figure 4, thus firmly anchoring the eyelet to the fiber.

It is to be noted that if the parts 4 and 6 were not spread the eyelets would not be anchored, and the inventor herein has made an important discovery in ascertaining that a fibrous material must be used, so that when the material is rendered concavo-convex in cross section, as above noted, these parts 4 and 6 will diverge and therefore afford a firm anchorage for the eyelets.

While heat has been specified as one of the agents used, in the making of this book back,

it is not absolutely necessary to employ heat in this connection, although when it is employed it greatly shortens the time necessary to produce such back. Pressure alone will bring about the results hereinbefore described but will consume more time in the absence of heat.

What is claimed is:—

1. A back for loose leaf books made from a hard fibrous material having loose leaf structure-fastening means embedded and anchored therein by the application of pressure.
2. A back for loose leaf books, comprising a hard fibrous material, means embedded therein under pressure for securing thereto a

loose leaf structure, said means being anchored within said material by the pressure applied to render such material concavo-convex in cross section.

3. A back for loose leaf books, comprising a hard fibrous material, elongated eyelets and base portions therefor having downwardly extending parts, said base portions being embedded in said material under the application of pressure, said material being formed by said pressure into a concavo-convex shape in cross section whereby the eyelets are anchored therein.

In testimony whereof I affix my signature hereto.

JOHN SCHADE.
